E. G. SWIGERT

CAST STEEL LADLE

Filed Aug. 31, 1925

UNITED STATES PATENT OFFICE.

ERNEST G. SWIGERT, OF PORTLAND, OREGON.

CAST-STEEL LADLE.

Application filed August 31, 1925. Serial No. 53,525.

My invention relates to ladles and other containers by which molten metal is moved about in smelters, and my invention relates especially to ladles used in copper smelters, 5 which because of their large size and thick walls are subjected to unequal expansion in their inner and outer surfaces when heated by the molten metal within the ladle. In other words the molten metal poured into 10 the ladle heats first the interior surface thereof and the heat conducted through the thick walls to the outer surface of the ladle is not sufficient to raise the latter surface to the same temperature as that of the inner 15 surface; in consequence such unequal heating causes unequal expansion of the inner and outer portions of the side walls and the bottom of the ladle. The inner portion of the ladle wall is restrained in its expansion 20 by the cooler outer surface of the wall and is subjected to compression, but since the metal in this portion of the wall and bottom becomes partially fluid it pushes inward forming protuberances like minute corrugations or ridges. Then when the ladle is 25 emptied, the interior of the wall has to cool through a greater range of temperature than the outer portion and thus undergoes greater shrinkage. But the interior shrinkage is 30 again restrained by the lesser shrinkage of the outer portion and the strain thus produced in the metal causes cracking or crazing of the ladle wall. This effect is more pronounced in the bottom of the ladle than 35 in the sides, and the cracks in the bottom frequently extend entirely through the ladle, resulting in fracture.

Increasing the thickness of the wall of the ladle in order to prevent the cracks extending 40 entirely through the wall is unsatisfactory for it increases difference in both expansion and shrinkage of the inner and outer wall surfaces, and results in the promotion of crazing and the formation of 45 wider cracks. If, on the other hand, the wall is made thinner, the strength of the ladle becomes insufficient for practical use.

The crazing, cracking, and fracturing of ladles as described above is not ordinarily 50 serious in the case of cast iron ladles, because the rate of cooling of cast iron and the extent of shrinkage do not produce internal strains of such magnitude as to cause serious fracture of the metal. But in the cast 55 steel ladles, the rapid cooling and relatively greater shrinkage acts upon the structure of

the metal to such an extent as to fracture the bottom of the ladle and render it practically worthless within a short time. It is therefore common practice at the present time to make ladles of cast iron rather than cast steel. For ladles of large size, however, such as those used in copper smelters, I prefer to make the ladles of cast steel, for the reason that cast iron is so brittle and easily shattered when struck by a sharp blow; and of course a ladle full of molten metal and subject to momentary breakage is a source of continual danger to the workmen.

The object of my invention is to produce a cast steel ladle, and the like, which is adapted to resist said dangerous crazing and cracking tendency, by neutralizing the causes of such effects.

I attained my object by the discovery that said crazing and cracking tendency may be substantially eliminated by a change in the method of making cast steel ladles, namely: by casting the bottom thereof of convex-concavo form, and substantially uniform thickness, the convexity being on the interior of the bottom, whereby the bottom of the ladle is adapted to be bent or flexed inward and outward, and thus to accommodate and neutralize the strains in the metal due to said unequal expansion and shrinkage, caused by the unequal temperatures induced in the interior and exterior surfaces of the ladle by the heat of the material carried therein. In this way the fracturing of the ladle by said unequal expansion and shrinkage is minimized to a negligible degree. In fact, in my practice I found that said fracturing tendency was eliminated.

The details of construction of a preferred embodiment of my invention are hereinafter described with reference to the accompanying drawings, in which:

Fig. 1 is a plan view of a ladle embodying my invention; and

Fig. 2 is a longitudinal section therethrough taken on the line 2-2 of Fig. 1.

My improved ladle *a* is an integral structure comprising a body of convenient form, having walls and a bottom of substantial and uniform thickness. The ladle is provided with trunnions *b*, a pouring spout *c*, spaced leg portions *d* and a tipping eye *e*, which serve their usual purposes.

The intense heat from the molten metal with which the ladle is filled, causes the

walls of the ladle to become correspondingly heated. When the ladle is filled with molten metal the heat from the latter is of course communicated to a greater degree to the interior surface of the ladle than its exterior surface, difference in the heating of its inner and outer surfaces varying according to the thickness of the walls of the ladle and the heat conductivity of the material of which the walls are made. These walls of the ladle frequently are from four to six inches thick, in large-size ladles used in copper smelting, and when ladles of this type are made of cast steel the difference between the heating of their interior and exterior surfaces causes the crystalline structure of cast steel to give way under the stresses built up by differential expansion of the different portions of the walls. The point at which the fractures usually occur is in the bottom a' of the ladle. The heat applied to the inner surface tends either to deform the curvature of the bottom or to elongate it relatively to the outer surface and the latter being relatively cooler tends to resist said elongation. The inner surfaces being heated to a relatively high degree thus become partially fluid and thus the internal stresses within the wall causes welts or ridges to be formed upon the inner surface of the bottom of the ladle. When said stresses are relieved upon cooling, the contraction of the metal does not cause said protuberances to recede, but instead causes cracks to form between said ridges or welts. Said cracks extend partially through the bottom of the ladle, and the successive heating and cooling

action to which the ladle is subjected by conveying and discharging batches of molten metal, soon extends these cracks completely through the ladle so as to render the same worthless. To prevent such result I form the bottom a' of the ladle with a concavo-convex central portion a^2 . As shown in Fig. 2, the bottom of the ladle is not increased in thickness and is substantially of uniform thickness throughout and thus the inner surface of said concavo-convex central portion is curved upon an arc having a greater radius than the concentrically curved outer portion of the bottom. The result of so forming the bottom of the ladle is, the bottom is adapted to be bent or flexed inward and outward more or less in accommodating said unequal expansion of its inner and outer surfaces, and in that way the detrimental strains caused in the metal are neutralized and substantially eliminated, thus avoiding the danger of fracturing the ladle, and not only prolonging the life of the latter but also protecting the workmen using it.

I claim:

A ladle adapted for carrying molten metal inducing interior heating, the bottom of the ladle being formed of substantially uniform thickness, and with an incurved area whereby the linear dimensions of the bottom between diametrically opposed points in the side walls of the ladle are increased to permit unequal expansion and shrinkage of the bottom and neutralize the strains tending to cause crazing and cracking of the bottom.

ERNEST G. SWIGERT.
